MOISTURE RESPONSIVE SIGNALING DEVICE

Benjamin D. Kaplan, Burbank, Calif.

Application August 2, 1952, Serial No. 302,310

9 Claims. (Cl. 200—61.05)

1

This invention relates to signaling devices and more particularly to signaling devices adapted to give a signal when affected by moisture.

Several devices of the above nature have been proposed for giving a signal when exposed to moisture such as rain or partially conductive liquids in one form or another. For example, the systems find use in informing an attendant of the wetting of a bed or bed clothes by the occupant thereof. The devices have generally comprised a pair of flexible flat coplanar electrodes mounted on or imbedded in an insulative pad member which may be placed in an infant's bed, or in a location where the presence of moisture is desired to be detected. The electrode surface edges are disposed adjacent one another in such a manner that a conducting liquid on the pad surface will electrically bridge and short circuit the electrodes to complete a power circuit. The signaling mechanism itself, such as a bell or light, for example, may be actuated by a relay in the power circuit. To increase the area responsive to the moisture, the electrodes have been interleaved in such a manner that the short circuiting can be effected at several different portions on the pad member surface.

While these prior systems have been satisfactory to some extent, they have tended to be bulky and cumbersome. Further, the interleaving type electrode design lengthens considerably the electrical path that the current must follow. This is especially the case when the short circuit is effected at a point on the pad spaced a considerable distance from the electrode terminals. In the interests of flexibility and portability, the electrodes must necessarily be thin in their third dimension. This additional path length therefore offers a high resistance to current flow and consequently reduces the reliability of the device. Thus, for example, while the actual current flow between the electrodes necessary to actuate a relay is generally quite small, the conductivity of the actuating liquid may be so poor that its resistance in series with any additional resistance due to the interleaving electrode structure, is oftentimes sufficient to prevent the current from actuating the signaling mechanism.

An additional difficulty with these past structures is that in order to insure that the electrode interleaving edges are insulated from one another, an appreciable space between these edges would have to be maintained. This is because these electrodes have in the past taken the form of metal foil or conductive flat strips glued or otherwise secured to the pad member surface and thus subject to slippage into contact with one another, especially during the moulding or

2

securing process. The effectiveness of the moisture pad is impaired by a large space to be bridged by the liquid since the resistance path through the liquid is greatly increased.

It is an object of the present invention, accordingly, to provide a moisture responsive device which is considerably more flexible and portable than has characterized prior designed systems, and yet is extremely reliable in its electrical operation.

More particularly it is an object of the invention to provide an improved moisture responsive pad of the type described in which the electrical resistance of current paths in the electrodes is minimized.

A further object is to provide a signaling device in which the electrode array and pad is such as to render the system many times more sensitive to moisture than has been achieved in the past.

These and other objects of the invention are attained by providing what may be termed a "three dimensional" type moisture responsive pad in contra-distinction to the "two dimensional" prior systems in which the electrodes were coplanar. In general, the invention comprises a flexible flat pad member having deposited on one surface thereof a conducting material constituting a first electrode of relatively large surface area. Portions of this electrode surface are covered by an insulating material. This insulating material may be treated with a salt bath such that any liquid falling on it will be rendered at least partially conductive. The insulating material in turn has deposited on its surface a conducting material constituting a second electrode. The electrodes are thus spaced apart, by a thickness corresponding to the thickness of the insulating material, in substantially parallel planes when the pad member is lying flat. The portions of the first electrode surface not covered by the insulating material are exposed so that any moisture on the pad member surface will readily effect a short circuit between the electrodes.

In a specific embodiment, the insulating material may take the form of a detachable second flexible pad member upon which the second electrode may be easily deposited. On the other hand, the insulating material may constitute an insulative coating spread directly on portions of the first electrode surface, the second electrode surface being deposited on this coating to form an integral unit.

With either of these arrangements it will be seen at once that the electrical path resistance through the electrodes is materially reduced be-

cause of the infinite number of parallel paths the current can follow on each electrode to the terminals of the pad member. Furthermore, the feature of depositing the electrodes directly on the pad member and insulative material provides a device which is extremely flexible and portable.

A better understanding of the invention will be had by referring to the accompanying drawings, in which:

Fig. 1 shows in perspective one embodiment of 10 the moisture pad and electrode arrangement;

Fig. 2 is an enlarged edge view of the pad member of Fig. 1 as an assembled unit;

Fig. 3 illustrates a top view of another embodiment of the invention together with a schematic 15 diagram of the alarm circuit;

Fig. 4 is a cross-sectional view as seen along the line 4-4 of Fig. 3;

Fig. 5 shows in perspective still another form the moisture pad may take in accordance with 20 the invention.

Referring to the drawings, there are shown signaling devices particularly suited for indicating the wetting of a bed by an infant, for example. For this purpose, it is desirable that the moisture responsive pad be light, rugged, and extremely flexible so that when it is laid flat in a bed or crib its presence will not be uncomfortable to the occupant. While features of the present invention render the signaling device as shown in the drawings particularly suitable for this particular use, the invention is not to be thought of as limited solely to this application.

In Fig. 1 the device is shown as comprising a flexible pad member 10 having a first electrode 11 on its upper surface as shown. Although electrode 11 is preferably formed by depositing conductive material directly on the pad member surface, it may, instead, constitute a flexible metal foil secured to or imbedded in the surface of the pad. A metallic terminal 12 secured to an extension 11' of electrode 11 passes through pad member 10 and is adapted to be electrically connected to a cooperating terminal 12' on a detachable cord support 13.

A second pad member 14 made of insulative material adapted to cover partially electrode 11 has deposited or imbedded on its upper surface a second electrode 15 as shown. Electrode 15 also includes an extension 15' to which a metallic terminal 16 is secured and adapted to extend through pad member 14 and a cooperating opening in pad 10 (not shown) to a second terminal 16' on the cord support 13. Pad member 14 also includes at each of its four corners snap means cooperable with corresponding snap sockets on the corners of the lower pad member 10. This arrangement permits the pad members to be secured together and corresponding electrodes to be connected to a cord extension leading from cord support 13. Cord extension 17 terminates in a jack 18 which may be conveniently plugged into an alarm circuit. Clearly, other means for securing the two pad members 10 and 14 may be employed. The feature of making the two pads separable facilitates cleaning the electrode surfaces.

One or more openings 19 passing through the second electrode 15 and pad member 14 are provided so that only a portion of the first electrode surface 11 is covered when the various elements are assembled. Portions of the first electrode 11 are thus exposed through openings 19 when pad 14 is covering the pad 10.

Fig. 2 shows the assembled unit from one end in exaggerated dimensions, the same reference

numbers designating the corresponding elements shown in Fig. 1.

In operation, the assembled unit may be laid flat in an infant's crib under the main sheet for example, and the extension cord 17 connected to a suitable alarm circuit. Wetting of the bed clothes or diapers by the infant will thus moisten the upper surface of the electrode 15 and the exposed surface of electrode 11 through openings 19 providing a conducting path between the electrodes. This action completes a power circuit which may contain a relay to operate a buzzer or light and inform an attendant of the wetting, or awaken the child.

Fig. 3 discloses such a circuit arrangement in schematic form connected to a modified type of moisture responsive pad. In this embodiment, a flat pad member 30 similar to pad 10 in Fig. 1 has a first electrode 31 deposited on its surface. Electrode 31 is partially covered by an electrically insulative coating 32, such as a suitable insulating paint, as shown in the cross-sectional view of Fig. 4. A second electrode 33 is deposited on the surface of the insulative paint, the electrodes 31 and 33 being respectively provided with extensions 31' and 33' for connection to a suitable signaling circuit. A plurality of openings 34 in the electrode 33 and insulative coating 32 leave substantial portions of the surface of electrode 31 exposed such that the electrodes 31 and 33 are readily short circuited by any moisture or liquid falling on the surface of pad member 30.

The associated power circuit may comprise a battery 35, relay coil 36 and switch 37 connected in series between the electrodes 31 and 33 as shown. Operation of the relay arm 36' serves to connect a signaling element, such as a light or buzzer 38, across the battery 35 by closing contact 39.

With this arrangement, and switch 37 closed, wetting of the pad member 30 will electrically connect the electrodes 31 and 33. Current from battery 35 will then flow around the circuit, operating relay 36 to close contact 39 and actuate the signaling element 38.

Fig. 5 discloses yet another form the invention may take. In this embodiment a flexible pad member 50 of insulating material has a first electrode 51 deposited or otherwise secured to one surface of the pad. A second electrode 52 is similarly applied to the opposite surface of the pad. As in Figs. 1 and 3, suitable electrode extensions 51' and 52' may be provided for connection to a suitable alarm circuit 53.

A plurality of openings 54 extending through both electrodes 51 and 52 and pad member 50 permit any moisture or liquid to electrically short circuit electrodes 51 and 52 when the pad member is lying on a bed sheet or mattress. This action obtains because of the absorbing nature of the sheet or mattress which serves to moisten the bottom electrode 52 from moisture passing through the openings 54.

In the various forms of the invention as illustrated in Figs. 1 to 5, the flexible pad member may comprise poly-vinyl chloride, known under the trade name of "Vinylite." This material is highly flexible and has good electrical insulating properties. The electrodes themselves may comprise silver, deposited directly on the surface of the "Vinylite." A suitable screening material may be used when applying the insulative paint and second electrode to the pad member in Fig. 3 to provide the openings 34.

It will be appreciated that the embodiments

disclosed in Figs. 1 to 5 provide a highly flexible and rugged moisture-responsive signaling device. Further, the reliability of operation of the pad member in the presence of only small quantities of moisture is greatly enhanced due to the extremely close spacing of the electrodes. This close spacing is possible because of the "three dimension" construction feature wherein the electrodes are separated only by the thickness of the insulating material.

By providing a plurality of registering openings in the second electrode and the insulative layer thus exposing portions of the surface of the first electrode, the electrical bridging of the two electrodes by any moisture laden bed clothes or liquid on the pad surface is readily effected. In the case of the wetting by an infant, the salt in its urine is sufficient to provide a partially conducting liquid. On the other hand when the insulating material has been treated in a salt bath for example, any liquid such as rain will be rendered conductive upon falling on the pad. It should be understood of course that openings of any suitable configuration may be employed. The circular and elongated slot openings depicted in Figs. 1 and 3 respectively are shown merely by way of example. It is preferable to have the openings distributed over a large area of the pad surface so that moisture falling anywhere on the surface will effect the short circuit.

It is also to be appreciated that the particular electrode arrangement provides a low resistance path from the point where the electrodes are shorted to the terminal points on the pad. This is because the whole surface of each pad respectively is utilized to conduct current to the pad terminals. Thus each pad surface effectively provides an infinite number of paths in parallel leading to the respective terminal. Also, these pads do not necessitate the use of molds or dies in their manufacture.

Various modifications within the spirit of the present invention will readily occur to those skilled in the art. Thus, while snap means have been disclosed in Fig. 1 for assembling the various elements, any other suitable fastening means may be employed. For example, the extension cord may be directly secured to the electrodes by any suitable connecting means. Also, it is not necessary that the respective pads be fastened together; one may simply rest flat on top of the other. Further, the electrodes may constitute any type of flexible conducting material secured to or imbedded in the insulative surfaces, such as metal foil for example. Any suitable alarm circuit or responsive mechanism may also be substituted for the circuit of Fig. 3 such as a sensitive electronic circuit wherein the sensitivity of the device may be greatly increased by feeding the signal to the control grid of a vacuum tube.

Moreover, while the apparatus has been described in detail with reference to a signaling device for indicating the wetting of a bed, the invention has many other useful applications. For example, it may be used to actuate window or door closing mechanisms in response to rain drops falling on the pad member.

The invention therefore is not to be thought of as limited to the precise embodiments disclosed.

I claim:

1. A moisture responsive device comprising a flexible pad member made of electrical insulating material, a first electrode comprising a continuous layer of electrically conducting material

on one surface of said pad member, and a second electrode containing a plurality of openings therethrough on the opposite surface of the pad member whereby the first and second electrodes are spaced apart by said pad member in substantially parallel planes when the pad member is lying flat.

2. A device according to claim 1, in which said electrodes comprise conductive metal foil secured to the opposite surfaces of said pad member respectively.

3. A signaling device comprising a flexible pad member, a first electrode deposited on one surface of the pad member, electrical insulating means comprising an insulative-coating covering portions of said first electrode, a second electrode deposited on only those portions of the insulative coating covering the first electrode, whereby the portions of the first electrode not covered by the insulative coating are exposed.

4. A moisture responsive device comprising in combination: a first flexible pad member, a first electrode on at least one surface of the pad member, a second flexible pad member made of electrical insulating material and containing a plurality of openings therein distributed over a substantial area of the second pad member, a second electrode covering said second pad member and containing openings registering with the first mentioned openings, means for securing the second pad member to the first pad member whereby the first and second electrodes are spaced apart by said second pad member and portions of the first electrode surface are exposed through said openings.

5. A device according to claim 4, in which said electrodes are imbedded in said pad members.

6. A moisture responsive device comprising a flexible pad member, a first electrode deposited on one surface of the pad member, electrical insulating means coated over portions of the first electrode whereby a plurality of openings exposing other portions of the first electrode surface are distributed over a substantial area of the surface, a second electrode deposited on only those portions of the insulative coating means covering the first electrode surface, whereby said electrodes are electrically insulated from each other by said insulative coating means.

7. A moisture responsive device comprising a first electrode made of conductive material in the form of a flexible pad, a second electrode similar in dimensions to said first electrode and containing a plurality of openings therethrough extending over a substantial portion of its area, said second electrode being adapted to lie over said first electrode, and electrical insulating means disposed between said electrodes.

8. A device according to claim 7, in which said first electrode comprises a continuous conductive layer, conducting portions thereof lying directly beneath said openings in the second electrode.

9. A device according to claim 8, in which said insulating means contains a plurality of openings registering with the openings in said second electrode whereby said conducting portions are exposed.
